UNITED STATES PATENT OFFICE.

WILLIAM A. WOOD, OF MONTREAL, CANADA.

DESIGN FOR A THIMBLE.

SPECIFICATION forming part of Design No. 21,901, dated October 18, 1892.

Application filed June 14, 1892. Serial No. 436,720½. Term of patent 7 years.

To all whom it may concern,

Be it known that I, WILLIAM ARCHIBALD WOOD, a subject of the Queen of Great Britain, and a resident of Montreal, in the District 5 of Montreal and Province of Quebec, Dominion of Canada, have invented and produced a new and original Design for Sewing-Thimbles, of which the following is a specification, reference being had to the accompanying 10 drawings, in which—

Figures 1, 2, 3, and 4 show side, front, and back views of the thimble.

The working surface comprehends indented top, back, and side portions A A' A² A², while the remaining section B forms a distinctive 15 panel on the front.

What I claim is as follows:

The design for a sewing-thimble, substantially as shown and described.

WILLIAM A. WOOD.
